UNITED STATES PATENT OFFICE.

AGNES H. REDHEFFER, OF ST. LOUIS, MISSOURI.

CORD ATTACHMENT FOR WINDOW-SHADES.

SPECIFICATION forming part of Letters Patent No. 777,140, dated December 13, 1904.

Application filed September 8, 1903. Serial No. 172,214. (No model.)

To all whom it may concern:

Be it known that I, AGNES H. REDHEFFER, a citizen of the United States, residing at St. Louis, in the State of Missouri, have invented 5 certain new and useful Improvements in Cord Attachments for Window-Shades, of which the following is a specification, reference being had therein to the accompanying drawings.

This invention relates to improvements in 10 a cord attachment for window-shades; and it consists in the novel arrangement, construction, and combination of parts, as will be fully hereinafter described and claimed.

The object of this invention is to construct 15 a device to be attached to the stiffening-bar of the window-shade, the said device containing the regulating-cord.

A further object is the cord is normally concealed from view by being retained within 20 a casing by a spring-drum, yet permitting the cord to be partially withdrawn for the adjustment of the shade.

Figure 1 is a perspective view of a window-shade, showing the improved device in position, the cord partially withdrawn. Fig. 2 is 25 a vertical sectional view taken through the casing, showing its internal construction. Fig. 3 is a vertical cross-sectional view of the same, showing its construction and relative position 30 to the shade.

In the construction of the device as shown, 4 indicates a casing provided with a vertically-projecting flange 5, located at one side thereof, and provided with suitable screw-holes 35 through which screws, brads, or the like may be inserted for attaching said device to the stiffening-bar 6 of the shade. The casing 4 has also a housing 7, in which is located a revolving spring - actuated drum 8, loosely 40 mounted upon a stationary shaft 9, the said shaft being supported in the casing 4. A flange 10 is formed on one side of the drum 8 and provided with notches 11, in which is adapted to engage the pawl 12, which is pivotally connected to the side wall of the casing 4. (See Fig. 2.) To the outer circumference of the drum proper is secured one end of the cord 13, and around said drum the said cord is wound.

50 The cord is prevented from leaving the

drum by means of the flanged edge 14. A hole 15 is formed in the bottom of the casing 4, through which the opposite end of said cord is passed and attached to a knob 16, by which the operator may partly withdraw said cord 55 when desiring to adjust the position of the shade.

A spiral spring 17 is located within the drum 8, one end thereof rigidly secured to the inner periphery and the other end rigidly 60 secured to the shaft 9.

By pulling upon the cord 13 the drum will revolve within the casing, at the same instant winding up the spiral spring until its movement is limited. The shade is then adjusted, 65 and by instantly releasing said cord the same will be rewound upon the drum by the unwinding of the spiral spring until the knob comes in contact with the casing, completely concealing the cord from view.

If desired to have the cord or a portion thereof to project from the casing, it is allowed to slowly rewind until the pawl 12 engages the notch 11 in the flange.

The device is made ornamental and dispenses 75 with the inconvenience of the common cord and marring of the woodwork. It has features of novelty and utility.

Having fully described my invention, what I claim, and desire to secure by Letters Patent, is—

1. A device of the class described comprising a casing, a flange projecting upwardly from said casing, said device attached to the stiffening-bar of the window-shade, a drum, a shaft for supporting the drum within the casing, flanges formed on each side of the drum, a cord secured to the drum and adapted to wind around the same between the flanges, a spiral spring located in the drum for controlling said drum when manipulated by the action of the cord substantially as specified.

2. A window-shade provided with means for adjustably securing its cord thereto, said means comprising a casing having devices by 95 which it is secured to the stiffening-bar of said shade, and a housing having an opening at one end only through which the cord is adapted to be drawn, a drum rotatably mounted in said housing and to which one end of said cord is 100

secured, a spring connected with said drum and serving to rotate the same in one direction so as to draw the cord into the housing when the cord is released, and a pawl engaging said

5 drum.

3. A window-shade provided with means for adjustably securing its cord thereto, said means comprising a casing having devices by which it is secured to the stiffening-bar of said shade, and a housing having an opening at one end only through which the cord is adapted to be drawn, a drum rotatably mounted in said

housing and to which one end of said cord is secured, and a spring connected with said drum and serving to rotate the same in one 15 direction so as to draw the cord into the housing when the cord is released.

In testimony whereof I affix my signature in presence of two witnesses.

AGNES H. REDHEFFER.
